UNITED STATES PATENT OFFICE.

GUSTAV BUCKY, OF BERLIN, GERMANY, ASSIGNOR TO SIEMENS & HALSKE, A. G., OF BERLIN, GERMANY, A CORPORATION OF GERMANY.

METHOD OF AND APPARATUS FOR PROJECTING RÖNTGEN IMAGES.

1,164,987.

Specification of Letters Patent.

Patented Dec. 21, 1915.

Application filed February 3, 1914. Serial No. 816,137.

To all whom it may concern:

Be it known that I, GUSTAV BUCKY, a German citizen, and resident of Berlin, Germany, have invented certain new and useful 5 Improvements in Methods of and Apparatus for Projecting Röntgen Images, of which the following is a specification.

In the practice of Röntgenography and Röntgenoscopy, as known, it has been found 10 that a veiling of the image resulting into a foggy appearance of the picture is due to the secondary Röntgen rays which are generated when the primary Röntgen rays pass through a body.

15 It is the object of my invention to devise an apparatus which prevents the injurious effect of these secondary rays upon the Röntgen image on a photographic plate as well as on a fluorescent screen in a very 20 perfect manner and so that it will yet be possible to obtain the entire picture by a single photographic process.

According to this invention between the 25 plate carrying the Röntgen image and the body a grid or screen is provided which is composed of several chambers or ducts not unlike to the structure of a honeycomb. These ducts or chambers are made of a material which is little permeable for Röntgen, 30 rays and the walls of these chambers are preferably so arranged that they will be positioned in the direction of the primary rays, so that they will not obstruct the passage of the same. The arrangement of the 35 chambers in said grid will enable one to obtain a most effective protection from secondary rays which are generated in the body, for these injurious rays will be prevented from arriving at the carrier of the 40 image the greater the depth of the several chambers is and the smaller their cross-section. This condition can be fulfilled only if the walls of said chambers are parallel to the direction of the rays.

45 The screen or grid can be of plane or spherical form. In order not to obtain an image of the grid which may sometimes be undesirable, especially in case a photograph be taken, the grid may be movably mounted 50 and may be provided with a contrivance for imparting motion to the same. This motion should be rather quick and may

either be a linear, oscillating, circular, elliptical or any similar motion, so that shadows which are cast by the grid will not have any 55 influence upon the image. Furthermore devices are preferably employed which permit an accurate adjustment of the Röntgen tube above the center of the grid and in a distance corresponding to the inclination of 60 the walls of the chambers therein.

My invention will be more fully understood by reference to the accompanying drawings, of which—

Figure 1 is a diagrammatic view of the 65 general arrangement comprising a Röntgen tube, a body to be photographed and the means for preventing secondary Röntgen rays or glass rays to pass to the photographic plate, Fig. 2 a grid which is a 70 preferable form of the afore-mentioned means of Fig. 1, Figs. 3 and 4 a view and cross-section respectively of a grid according to Fig. 2 having the form of a spherical calotte, Fig. 5 showing a grid whose carrier 75 may be removed by dissolving the same, for instance in a liquid, Figs. 6 and 7 are a side view and plan view respectively of an apparatus for securing the centering of the Röntgen tube with respect to the direction 80 of the walls of the chambers of the grid. Figs. 8 and 9 are a side view and a plan view respectively of a further arrangement for centering the Röntgen tube above the grid, and Figs. 10 and 11 are a top and side 85 view respectively of a device for imparting a motion to the grid for rendering non-injurious the effect of the shadows of the walls thereof.

In Fig. 1, 1 represents the Röntgen tube, 90 2 the body from which an image is desired to be taken on a photographic plate 3 or on a fluorescent screen arranged at this place instead of a plate. Between the body and the plate a grid 4 is provided, said grid having chambers whose walls are positioned to coincide in direction with that of the primary Röntgen rays, so that the prolongations of the walls of said chambers will all intersect at the anticathode 5 of the Röntgen 100 tube. In Fig. 2 the grid with its chambers is shown in a plan view representing the exact form of the chambers or ducts of said grid. This figure shows three modifications of the

grid or screen. In the upper part of Fig. 2 there are shown parallel and unidirectional walls forming the ducts or chambers of the grid. In the middle part of Fig. 2 a grid is shown which consists of walls intersecting each other rectangularly, so that individual ducts or chambers of rectangular cross-section will result. In either case the walls forming the grid or screen are so arranged that they will be positioned in the direction of the Röntgen rays, as can clearly be seen in Fig. 1. The third or lower part of Fig. 2 shows a construction of the ducts or chambers of the grid whereby cylindrically bent metal sheets are used for making the chambers or ducts of the grid, said metal sheets being connected with each other by short connecting bridges, as indicated in the drawing. From the three forms of the grid or screen represented in Fig. 2 I regard that shown in the middle part of this figure as the most advantageous form of the ducts or chambers of the grid.

In order to illustrate the action of the grid, two points p_1 and p_2 are assumed to be the points of issue of secondary rays, said points being near to the underside of the body k from which a Röntgen photograph shall be taken. In case of sufficient depth and sufficiently small cross-section of the chambers only those secondary rays issuing from p_1 and p_2 will arrive upon the plate 3 which have approximately the same direction as the primary Röntgen rays, while the remaining secondary rays will be absorbed by the walls of the chambers of the grid. Therefore essentially only evenly directed rays will serve to generate an image and therewith the veiling or fogging of the latter will be avoided.

For taking photographic Röntgen pictures it is advantageous to build the grid into the case surrounding the photographic plate.

Besides the grid serving for obstructing the rays issuing from the body in the arrangement shown in Fig. 1 a like grid 6 is provided in order to render non-injurious the secondary rays issuing from the glass wall of the Röntgen tube, the so-called glass rays. The walls forming the several chambers of this grid are likewise so directed that they will coincide with the direction of the primary rays in order to permit the passage of the latter.

In Figs. 3 and 4 a grid is shown in a view and a cross-section respectively, said grid having the form of a spherical calotte. This form of grid on the one hand has the advantage that it will eventually better fit the body to be photographed and that on the other hand the manufacture of exactly radially directed walls of the chambers of said grid will be facilitated. The width of

the chambers or the width of the meshes of said grid may be made as narrow as desired and the grid itself accordingly become of a very small thickness. A grid of this kind may for instance be manufactured in such a manner that, as apparent from Fig. 4, a form of the grid with parallel walls is cut into a plate 6 which plate is made from a material of good permeability for Röntgen rays and having preferably the property of emanating few secondary rays, such as for instance celluloid. These cuts now are filled with a material 7 which easily absorbs Röntgen rays and which preferably emanates few secondary rays. This plane grid is then bent into spherical form, so that by having the anticathodes positioned in the center of the spherical calotte the walls of the grid will exactly coincide with the direction of the primary Röntgen radiation. As a filling material for the cuts or chambers of the grid lead dust may be used together with a binding medium such as red lead or the like. This form of the grid has the advantage that by reason of the coherent celluloid plate the lead grid may be made very thin, so that it will accordingly cast only little shadow upon the plate.

If the filling material is pressed under sufficient pressure into the cut spaces, a thin coherent grid will be obtained. If for a plate in which the grid form is cut a material is chosen which afterward may be easily removed, for instance, a material which is soluble in certain liquids, according to the new process, also a coherent grid can be made without having a special carrier. In this case also one is enabled to do away with the weak absorption of the primary Röntgen rays taking place in the first described modification of the plate carrying the grid. This plate may for instance be given spherical shape by pressing the same into a proper form, and after said plate has assumed spherical shape it may further be finished or worked upon its surface by planing or a similar mechanical operation in such a manner that plane limiting surfaces will be made thereon. For this purpose the thickness of the plate when being in spherical form must be rather considerable in order to obtain a sufficient thickness of the plate after the aforementioned plane limiting surfaces have been made thereon. Another way of making the spherical grid or screen according to my invention consists therein that a grid form with parallel walls is first cut into a plate. Thereupon the grid is filled with a material which is impermeable for Röntgen rays, such as for instance asphalt, and then a spherical shape is given to the plate and the grid separated by dissolving the same in a liquid such as benzine, kerosene and the like.

A process for making plane grids consists therein that first the grid with its carrier is made in the form of a calotte, whereupon either side is worked by a planer or the like.

5 In this case the grid walls themselves must form a firm unit or they must be well joined with the carrier by means of putty or the like. Fig. 5 shows in a cross-section a grid of this kind whose carrier may also be removed by dissolution or the like.

In Fig. 6 I have shown an example of an arrangement for obtaining a centered position of the Röntgen tube relatively to the walls of the grid. The Röntgen tube 1 here-
 15 by is mounted in a holder 8 which is fixed on a U-shaped frame 9. This frame may be fixed on a table or tripod by means of a pivot 10 and also carries a holding device 11 permitting to receive the grid 4 and
 20 eventually also the photographic plate 3 in such a place that the anticathode of the Röntgen tube will be exactly positioned at the point of intersection of the planes of all walls of the grid. This arrangement can be
 25 advantageously used in case stereoscopic pictures are desired, in case of which with the displacement of the Röntgen tube also the grid must be shifted. In this case only a shifting of the frame 9 will be required.

30 In Figs. 8 and 9 I have shown a further arrangement of centering the Röntgen tube above the grid. Hereby it is assumed that the proper distance of the tube from the grid is secured in another way by proper ar-
 35 rangements. Thereby at the frame 11 carrying the grid 4 a trestle 12 is provided carrying at its upper end an iron tube 14 which is rotatable around a journal 13. A stop 15 limits the motion of this arm in the one di-
 40 rection and more particularly as soon as this arm will be positioned exactly above the center plane of the grid 4. The arm 14 is equipped with an extension 16 telescoping therewith, and carries a sighting device
 45 which consists of a tube 17 within which there are spider threads 18. At its under end the tube 17 is provided with an exten-
 50 sion 19 fitting said tube, which extension contains a mirror 20 inclined at an angle of 45°. As indicated by the dotted lines re-
 55 presenting the direction of rays issuing from the eye 21, by means of the mirror 20 and the spider threads 18 it may be exactly ascer-
 60 tained whether the anticathode 5 of the Röntgen tube 1 be positioned exactly per-
 65 pendicular above the center of the grid 4. After proper adjustment of the Röntgen tube, for the photographic exposure, the sighting device with the arm 14 is swung out of the actuating range of the grid in the direction as indicated by the arrow.

The trestle 12 is fixed by journals 22 fitting into sleeves at the frame 11 of the grid. The sighting device accordingly may

be fixed at the long or narrow side of the 65 grid, whereby the corresponding length of the swinging arm can be adjusted by moving its part 16 relatively to the part 14 and fixing the position by means of a screw.

For imparting motion, as above pointed 70 out, to the grid 4, the frame 11 thereof is pro-
 75 vided with two extensions 25 having circu-
 lar recesses, in which disks 26 are rotatably mounted which disks are eccentrically fixed upon axles 27. These axles are coupled by 75 means of conical gears 28 with a third axle 29 which latter may be rotated by means of a crank 30. Upon rotation of said crank through the eccentric disks a motion will be imparted to the extensions 25 and there-
 80 with to the entire grid 4, so that each point of said grid will describe a circular path. The eccentricity of the disks thereby is chosen, so that the diameter of the circle of motion, which for instance is indicated at 85 the point *p* at Fig. 10, will be just equal to the length of the side of the smallest squares of the grid.

The velocity of the drive must be such that the walls of the grid will not cast a 90 visible shadow upon the photographic plate or upon the fluorescent screen. For this purpose it is only required to rotate the crank 30 at the proper speed. Instead of using manual means for rotating the grid, 95 it is of course also impossible to use a clock fork or a motor.

Having thus described my invention I do not wish to be understood as limiting myself to the precise construction as shown and 100 described, since modifications may be made thereon without departing from the principle or sacrificing any of the advantages of this invention, but

I claim as new and desire to secure by Let- 105
 ters Patent of the United States:—

1. An apparatus for projecting Röntgen images, comprising a source of Röntgen rays, a plate carrying the Röntgen image and a grid or screen interposed between said source and said plate immediately upon the latter, said grid or screen being composed of 110 a number of chambers having walls of a form to obstruct passage of secondary Röntgen rays.

2. An apparatus for projecting Röntgen images, comprising a source of Röntgen rays, a plate carrying the Röntgen image, and a grid or screen made of a material which is little absorbing Röntgen rays and 115 emanating only few secondary rays which is arranged between said source and said plate immediately upon the latter, said grid or screen having a plurality of chambers with walls in the direction of the rays origi- 120
 125 nating from said source.

3. In combination with a Röntgen appa-
 ratus, a grid or screen composed of several

- chambers for screening off the secondary Röntgen rays, said grid or screen having partitions with walls directed toward the anticathode of the Röntgen tube.
5. 4. In combination with a Röntgen apparatus, a grid or screen of the form of a spherical calotte for screening off secondary Röntgen rays, said grid or screen having a number of partitions with walls of a direction to intersect at the anticathode of the Röntgen tube.
10. 5. In an apparatus for projecting Röntgen images, the combination of a source of Röntgen rays, a grid or screen with partitions to screen off secondary Röntgen rays, and means for centering said grid or screen relatively to said source.
15. 6. Apparatus for projecting Röntgen images comprising a Röntgen tube, a grid or screen with partitions to screen off secondary Röntgen rays, and a sighting device for centering the anticathode of said tube relatively to said grid or screen.
20. 7. In combination with a Röntgen apparatus, a source of Röntgen rays, a plate carrying the Röntgen image, and two grids or screens interposed between said source and said plate, one of which is positioned immediately upon said plate and the other near to said source, each of said grids or screens being composed of a number of partitions with walls which are evenly directed with the Röntgen rays issuing from said source.
25. 8. In combination with a Röntgen apparatus, a grid or screen having partitions with walls essentially positioned in the direction of the primary Röntgen rays and means for moving said grid or screen so as to prevent a visible shadow of said grid or screen on the image.
30. 9. In combination with a Röntgen apparatus, a grid or screen having partitions with walls essentially positioned in the direction of the primary Röntgen rays, and means for imparting a motion to said grid or screen, said motion having in every direction a maximum amplitude not surpassing that of the width of the meshes of said grid or screen.
35. 10. A grid or screen for Röntgen apparatus, having the shape of a spherical calotte with partitions having radially directed walls for being inserted into the path of Röntgen rays to have the intersecting point of said walls coinciding with the source of said Röntgen rays, said grid or screen consisting of a material which is little absorbing Röntgen rays and little emanating secondary rays, a filling for said grid or screen, said filling consisting of a material which is impermeable for Röntgen rays.
40. 11. The process of making a spherically shaped grid or screen having radially directed partition walls for screening Röntgen rays, which consists in cutting a grid form with parallel walls into a plate made from a material which is slightly absorbing Röntgen rays and slightly emanating secondary rays, filling said grid form with a material which is impermeable for Röntgen rays, and subsequently bending said plate into spherical shape.
45. 12. The process of making a spherically shaped grid or screen having radially directed partition walls for screening Röntgen rays, which consists in cutting a grid form with parallel walls into a plate made from a material which is slightly absorbing Röntgen rays and slightly emanating secondary rays, filling said grid form with a material which is impermeable for Röntgen rays, subsequently bending said plate into spherical shape and separating said grid from said plate by dissolving the same in a liquid.
50. 13. The process of making a spherically shaped grid or screen having radially directed partition walls for screening Röntgen rays, which consists in cutting a grid form with parallel walls into a plate made from a material which is slightly absorbing Röntgen rays and slightly emanating secondary rays, filling said grid form with a material which is impermeable for Röntgen rays, subsequently bending said plate into spherical shape and separating said grid from said plate by dissolving the same in a liquid.
55. 14. The process of making a spherically shaped grid or screen having radially directed partition walls for screening Röntgen rays, which consists in cutting a grid form with parallel walls into a plate made from a material which is slightly absorbing Röntgen rays and slightly emanating secondary rays, filling said grid form with a material which is impermeable for Röntgen rays, subsequently bending said plate into spherical shape, separating said grid from said plate by dissolving the same in a liquid.
60. 15. Apparatus for projecting Röntgen images, comprising a Röntgen tube, a plate carrying the Röntgen image, a grid or screen with partitions screening off secondary Röntgen rays, said screen being arranged between said source and said plate immediately upon the latter, and a sighting device for centering the anticathode of said tube relatively to said grid or screen.
65. 16. In combination with a Röntgen apparatus, consisting of a source of Röntgen rays and a plate carrying the Röntgen image, a grid or screen having partitions with walls essentially positioned in the direction of the primary Röntgen rays, said grid or

screen being arranged between said source and said plate immediately upon the latter, and means for keeping said grid or screen in motion, so as to prevent a visible shadow 5 of said grid or screen from being thrown on the image.
